RAILWAY TRUCK

William H. Meyer, St. Louis, Mo., assignor to
General Steel Castings Corporation, Granite
City, Ill., a corporation of Delaware

Application April 6, 1939, Serial No. 266,289

20 Claims. (Cl. 105—183)

The invention relates to railway rolling stock and consists in novel eight wheel truck construction and more particularly an eight wheel truck having a rigid frame in which all four axles of the truck are mounted.

It is one object of the invention to simplify the truck construction.

It is another object of the invention to avoid excessive weight as has characterized some eight wheel trucks due to the application of load to the truck frame, and particularly the wheel pieces thereof, at points on the wheel pieces spaced from points at which they are supported.

It is another object of the invention to equalize the truck load to all of the truck axles without utilizing an equalizing system which comprises springs and equalizers arranged end to end and without utilizing the truck wheel pieces as equalizers.

These and other detail objects of the invention as will appear from the following description are attained by the structure illustrated in the accompanying drawings in which

Figure 1 is a top view of an eight wheel truck embodying one form of the invention.

Figure 2 is in part a side elevation and in part a longitudinal vertical section taken on line 2—2 of Figure 1.

Figures 3 and 4 are vertical transverse sections taken on the corresponding section lines of Figure 1.

Figure 5 is a one-half longitudinal top view of an eight wheel truck embodying another form of the invention which includes a lateral motion bolster.

Figure 6 is a side elevation of the truck shown in Figure 5.

Figure 7 is a vertical transverse section taken on line 7—7 of Figure 5.

Figures 8 and 9 correspond to Figures 5 and 6 but illustrate another form of the invention.

Figure 10 is a longitudinal vertical section taken on line 10—10 of Figure 8.

Figures 11, 12 and 13 are transverse vertical sections taken on the corresponding section lines of Figure 9.

Figure 14 is a longitudinal vertical section corresponding to Figure 10 but illustrating another form of the invention.

The truck shown in Figures 1 to 4 includes wheels 1, axles 2, 3, 4 and 5, journal boxes 6 and drop equalizers 7 and 8 provided with seats 9 for the truck frame supporting springs 10. All of the above parts are of familiar form and in themselves do not constitute the present invention.

The truck frame is of unitary construction, preferably but not necessarily, formed of a single casting and includes wheel pieces 11 with depending pedestal legs 12 for slidably receiving 5 journal boxes 6, transverse transoms 13 and 14, end rails 15 and 16, longitudinal arms 17, and a transverse member 18 intermediate transoms 13 and 14 and provided with center plate elements 19 arranged to receive the truck load from vehicle body center plate. Side bearings 21 function in the usual manner to resist rolling of the vehicle body.

Elements 13, 14, 17, 18 and 19 comprise a center bolster structure whereby the truck load is received through the center plate and carried, through arms 17, to transoms 13, 14 and thence to the springs 10, equalizers 7, 8 and journal boxes 6 substantially independently of wheel pieces 11 which function mainly as ties between

10 the truck axles and as framing members to resist longitudinal braking forces and other forces and which cooperate with the remaining framing to resist twisting and to maintain the truck rigid. Since the load on transoms 13, 14 is transferred to wheel pieces 11 at the points of support of

15 the latter by springs 10, and since there are no equalizing levers pivoted on the wheel pieces intermediate their points of support, there are no vertical bending moments set up in the wheel pieces due to the vertical load thereon. Similarly the structure eliminates vertical bending moments from forces resulting from track joints and other rail inequalities which tend to apply continuous shocks on the usual truck frame.

20 Accordingly wheel pieces 11 may be made of relatively light cross section compared to the relatively heavy longitudinal arms 17 and transoms 13, 14 which carry the vertical load substantially directly from the transoms 13, 14 to the truck

25 springs and equalizers.

25 Wheel pieces 11, transoms 13, 14, arms 17 and transverse member 18 are all of substantially box section to provide maximum strength for the material used although the wheel pieces open 30 downwardly adjacent their pedestal legs to receive the ends of equalizer 7.

35 Preferably, but not necessarily, braces 20 are provided between wheel pieces 11 and arms 17 at the middle of the truck and opposite to member 18. These connections stiffen the wheel pieces 11 against lateral deflection.

40 Brake hanger brackets 22 depend from braces 20 and other brake hanger brackets are provided at 23. End rail 16 is shown depressed intermediate its ends and provided with a bracket 24

for mounting a brake cylinder (not shown) and inwardly and upwardly inclined braces 25 connect bracket 24 and transom 14.

If desired, the advantages of a lateral motion bolster may be embodied in an eight wheel truck of the general type described above and such a structure as illustrated in Figures 5 to 7 in which the truck wheel pieces 30 are of relatively light section from end to end and the center bolster longitudinal arms 31 are of relatively heavy section, the relation between these parts corresponding to that described above in connection with wheel pieces 11 and arms 17.

The center bolster is suspended from the truck frame by swing hangers 32, pivotally connected at 33 to cross transoms 34 and, at 35, to the ends of bolster arms 31 which are connected by transverse members 36. Transoms 34 transfer the load to wheel pieces 30 immediately over the springs 37 seated on equalizers 38 mounted on journal boxes 39 and wheeled axles 40 as in the form previously described.

To provide access to swing hangers 32 and to the brake gear (not shown) equalizers 38 extend more nearly straight between journal boxes 39 and this elevates springs 37 above the level shown in Figures 2 and 4 and requires corresponding elevation of the adjacent portion of wheel pieces 30. Part of the elevation of the springs is accommodated by housing the same in the wheel pieces as shown.

Obviously with a lateral motion center bolster there can be no tie between the same and the wheel pieces as shown at 20 in the form previously described. Accordingly side bearings 41 are carried exclusively on arms 31 and brake hanger brackets 42 are carried exclusively by wheel pieces 30. These are relatively unimportant details, the main feature being the transfer of the truck load from the center plate 42a to the truck springs and equalizers by longitudinal and transverse members which avoid setting up vertical bending moments in the wheel pieces.

Figures 8 to 13 illustrate a form of the invention which embodies what is essentially a three point support for the truck frame on the truck springs. The frame includes wheel pieces 45 with depending pedestal legs 46 receiving the axle journal boxes 47 similarly to the structures previously described. The journal boxes on the two left hand axles mount depressed equalizers 48 which carry springs 49, which support wheel pieces 45 at the ends of the frame cross transom 50 similarly to the structures previously described but the depressed equalizers 51 mounted on the journal boxes for the two right hand axles carry a cross equalizer 52, and spring seats 53 are positioned on cross equalizer 52 at points spaced inwardly from the longitudinal equalizers 51. Springs 54 are mounted upon members 53 and are received in and directly support the frame cross transom 55.

Transoms 50 and 55 are provided with concave seats 56 for rollers R on which rest bearings 57 on the ends of the bolster arms 58. The bolster includes a center plate member 59 through which the truck load is carried to the arms as previously described.

This arrangement provides for a more even distribution of the weight to the wheels. It is the same as a three-legged stool in which each of the three legs will always constitute a supporting member regardless of any unevenness of the flooring upon which it rests or any variation in the length of the legs of the stool. In a truck with a

four-point spring support, when subjected to any slight track irregularity or any slight variation in the support members of the truck, one of the four points would likely be underloaded, setting up greater stresses in the truck frame and increasing the possibility of the wheel leaving the rail.

In the cross equalizer arrangement, as shown in Figures 8 to 13, the weight is more evenly distributed to the wheels when the truck travels over irregularities in the track because the weight which is thrown to one side of the truck is transferred back to the other side by means of the cross equalizer. A low spot in the rail on one side of the truck would throw the weight to the other side, but the cross equalizer, due to its being fulcrumed or supported at its end portion on that side of the truck, transfers at least part of the load back to its fulcrum or support on the other side of the truck. The closer the spacing of the points of application of the load (springs) on the cross equalizer, the more nearly equal would be the distribution of the load.

The principal advantage of the three-point spring support is that it provides a safe operating arrangement as it tends to keep the wheels on the rails when the truck travels over uneven track or when conditions are such that the load is shifted toward one side of the truck. Another advantage is that there would be less weaving of the truck frame and less overloading of the truck springs.

The vertical loading is transmitted from the bolster arms to the transoms at substantially the same points as in the structures shown in Figures 1 to 7. On the left hand end of the truck the load is transmitted through the transom on that end of the truck to the wheel pieces at points directly above the springs mounted on the equalizers, resulting in bending moments, due to vertical loading, in the transom, but no bending moments, due to vertical loading, in the wheel pieces. On the right hand side of the truck the vertical load is transmitted directly from the bolster arms to the transom on that end of the truck and then directly to the springs and cross equalizer without subjecting the transom or wheel pieces to bending moments due to vertical loading.

Chafing plates 60 (Fig. 10) are provided between the center bolster and the truck frame transoms and stop plates 61 are also provided on the bolster brackets 62 to engage transom lugs 63 and prevent vertical displacement of the center bolster relative to the truck frame. Brackets 64 (Figs. 11 and 12) are provided on the cross transoms to form stops for limiting lateral movement of the bolster.

The concave upper and lower engaging faces of seats 56 and bearings 57 respectively, provide a lateral resistance centering means between the bolster and the truck frame.

Figure 14 corresponds to Figure 10, but shows a truck in which the bolster 70 is rigid with the truck frame transoms 71 and 72. The equalizing arrangement is the same as shown in Figures 8 to 13 and the right hand transom 72 and the wheel pieces are free of bending moments due to vertical loading, the same as in the other structure.

In both of the cross equalizer structures the right hand transom is made lighter than the left hand transom to compensate for the weight of the cross equalizer, 52 or 73, thus tending to keep the weight of a cross equalized construction the

same as a non-cross equalized or four-point spring support construction.

The construction may be varied in other ways than those illustrated and described, and the exclusive use of such modifications as come within the scope of the claims is contemplated.

What is claimed is:

1. In a railway truck, four wheeled axles, equalizers between and carried upon the end axles and adjacent axles, and a truck frame including continuous rigid wheel pieces supported on said equalizers, there being a bolster member, with a center plate at the approximate level of said wheel pieces, for receiving the truck load and transferring it to said wheel pieces at points adjacent the points of support of the latter from said equalizers whereby said wheel pieces are substantially free of bending moments due to the truck load.

2. A truck as described in claim 1 in which the bolster member and the wheel pieces comprise a rigid unitary frame structure.

3. A truck as described in claim 1 which also includes braces between the bolster member and the wheel pieces intermediate the points at which the bolster is supported on the wheel pieces.

4. A truck as described in claim 1 in which the bolster member is movable laterally of the truck relative to the wheel pieces.

5. In a railway truck, four wheeled axles, journal boxes thereon, equalizers between and supported upon adjacent journal boxes, springs on said equalizers between the boxes supporting the same, a continuous rigid wheel piece at each side of the truck mounted on all of said springs on that side of the truck, a center bolster for receiving the truck load, and means transferring the same to said wheel pieces at points immediately over said springs.

6. In a railway truck, four wheeled axles, journal boxes thereon, equalizers between and supported upon adjacent journal boxes, springs on said equalizers between the supports therefor, a rigid frame overlying all of said axles and mounted on all of said springs, transverse transoms abreast of said springs and extending between and carried by the sides of said frame, swing hangers suspended from said transoms at points on the latter spaced inwardly from the sides of said frame, and a center bolster having a portion for receiving the truck load and having arms extending longitudinally from said portion and transferring the load to said transoms at points on the latter spaced inwardly from the sides of said frame.

7. A truck as described in claim 5 in which the center bolster is movable laterally of the truck relative to the wheel pieces.

8. In a railway truck, four wheeled axles, equalizers between and carried upon adjacent axles, and a truck frame including continuous wheel pieces and transverse transoms between said wheel pieces forming a rigid structure supported on said equalizers, at points in transverse alignment with said transoms, a bolster member including a load receiving portion and arms extending longitudinally of the truck between and carried by said transoms and spaced inwardly from said wheel pieces, said bolster member also including a load receiving portion carried by said arms intermediate said transoms, said wheel pieces, transoms and bolster load receiving portion being located at substantially the same level.

9. A truck as described in claim 8 in which the longitudinal arms of the bolster member com-

prise relatively heavy sections and the corresponding parts of the wheel pieces comprise relatively light sections.

10. In a railway truck, four wheeled axles, journal boxes thereon, equalizers located between each end axle and the adjacent middle axle and supported by corresponding journal boxes, springs supported by said equalizers, a frame directly supported by said springs, and a center bolster, all portions of which are located approximately below the tops of the spring engaging portions of said frame, for receiving the truck load and transferring the same to said truck frame at points immediately over said springs.

11. In a railway truck, four wheeled axles, journal boxes thereon, equalizers between and supported upon adjacent journal boxes, springs supported by said equalizers, a frame supported by said springs and comprising continuous rigid wheel pieces at each side of the truck and longitudinally spaced transverse transoms between said wheel pieces, there being a center bolster, all portions of which are located approximately below the tops of the spring engaging portions of said frame, having a portion for receiving the truck load and having arms extending longitudinally from said portion and elements at the ends of said arms transferring the load therefrom to said transoms at points on the latter spaced inwardly from said wheel pieces and then to said springs, whereby said wheel pieces are substantially free of bending moments due to the truck load.

12. In a railway vehicle truck, four wheeled axles, longitudinal equalizers between and carried upon each pair of axles at opposite ends of the truck, a cross equalizer carried by the longitudinal equalizers between the two axles at one end of the truck, a truck frame supported at one end on said cross equalizer and at its opposite end on the corresponding longitudinal equalizers, a bolster member for receiving the truck load and supported on said frame adjacent its points of support from said cross equalizer and said longitudinal equalizers.

13. In a railway truck, four wheeled axles, journal boxes thereon, equalizers between and supported upon adjacent journal boxes, springs supported by said equalizers, a unitary rigid frame mounted directly on said springs and having continuous wheel pieces extending over all of said axles and including pedestals for slidably receiving said journal boxes, there being a center bolster at substantially the same level as said wheel pieces for receiving the truck load and transferring it to said frame at points adjacent to its supports on said springs.

14. In a railway truck, four wheeled axles, journal boxes thereon, equalizers located between each end axle and its adjacent middle axle and supported by corresponding journal boxes, springs supported by said equalizers, a single rigid frame including transverse transoms, said frame being directly supported by all of said springs adjacent to said transoms, and a center bolster for receiving the truck load and transferring it to the truck frame adjacent to said transoms, said center bolster being yieldingly mounted on said transoms.

15. In a railway truck, four wheeled axles, journal boxes thereon, equalizers located between each end axle and its adjacent middle axle and supported by corresponding journal boxes, springs supported by said equalizers, a rigid frame overlying all of said axles and mounted

on all of said springs and directly supported by all of said springs, said frame including wheel pieces and transverse transoms, said transoms having portions located at substantially the same level as the tops of said springs and adjacent to said springs, and a center bolster for receiving the truck load and having longitudinally extending arms for transferring the load to said transom portions.

16. In a railway vehicle truck, four wheeled axles, longitudinal equalizers between and carried upon each pair of axles at opposite ends of the truck, a cross equalizer carried directly by the longitudinal equalizers between the two axles at one end of the truck, springs carried on said cross equalizer at points spaced inwardly from said longitudinal equalizers, said springs, cross equalizer and its carrying equalizers comprising a yielding load-equalizing system having its center at the longitudinal center line of the truck, springs carried respectively by the longitudinal equalizers at the other end of the truck, said latter-mentioned springs and their carrying equalizers comprising individual yielding load-equalizing systems independent of each other and having their respective centers at the sides of the truck, and a frame for receiving the vehicle load and transferring it through said spring systems to said axles.

17. In a railway vehicle truck, four wheeled axles, longitudinal equalizers between and carried upon each pair of axles at opposite ends of the truck, a cross equalizer carried by the longitudi-

nal equalizers between the two axles at one end of the truck, a truck frame supported at one end on said cross equalizer and at its opposite end on the corresponding longitudinal equalizers, a bolster member for receiving the truck load and supported on said frame at points spaced inwardly of the truck from the points of support of said frame on said latter-mentioned equalizers and at points substantially over the points of support of

10 said frame on said cross equalizer.

18. In a railway vehicle truck, four wheeled axles, equalizers between said axles, a truck frame supported on said equalizers and comprising wheel pieces and transverse transoms, and a truck bolster member for receiving the weight of the vehicle body and transferring it to said transoms and wheel pieces at points on said frame adjacent its supports whereby said wheel pieces are substantially free of bending moments due to the truck load, said wheel pieces, transoms and bolster member being at substantially the same level and below a vehicle body carried by the truck.

19. A truck as described in claim 16 which includes a bolster and means supporting the same on the truck frame and providing movement of the bolster laterally of the truck and relative to the equalizers.

20. A truck as described in claim 16 which includes roller elements mounted on the truck frame and a bolster carried on said elements and movable thereon laterally of the truck frame.

WILLIAM H. MEYER.
